UNITED STATES PATENT OFFICE.

WILLIAM H. BRISTOL, OF NEW YORK, N. Y.

INDICATING AND RECORDING SYSTEM.

No. 880,273.

Specification of Letters Patent.

Patented Feb. 25, 1908.

Application filed September 1, 1906. Serial No. 332,998.

To all whom it may concern:

Be it known that I, WILLIAM H. BRISTOL, a citizen of the United States, and a resident of New York, in the county of New York and 5 State of New York, have invented certain new and useful Improvements in Indicating and Recording Systems, of which the following is a specification.

My invention relates to electrical systems 10 in which electrical apparatus is automatically controlled by the variations of a resistance shunted across said electrical apparatus; and it has for its object a system of this character in which the actual current 15 flowing is extremely small, and in which small variations of a controlling resistance produce considerable effects in the electrical apparatus controlled thereby.

For this purpose my invention consists 20 essentially of a constant source of electro-motive force feeding through a suitable resistance a divided circuit—one branch of which contains electrical apparatus automatically controlled by a variable resistance located in 25 the other.

The nature of my invention will be best understood in connection with the accompanying drawings, in which—

Figure 1 is a diagrammatic view of the 30 various electrical connections. Figs. 2 to 4 are views illustrating the application of my invention to the indicating and recording of temperatures. Fig. 5 is a view illustrating the application of my invention to the recording of a distant water level, showing also a local circuit.

Similar characters of reference designate corresponding parts throughout the several views.

40 Referring to the drawings, 10 designates an electrical indicating device adapted to indicate small currents, as a milliammeter of the standard type; or, as in Figs. 3 and 5, a recording device adapted to record the 45 movements of the pointer of such indicating devices. This recording device is preferably of the type disclosed in my prior patent #813,689, of Feb. 27th, 1906, as the movements of the indicating arm are usually extremely delicate having but little motive 50 power actuating them.

11 is a source of electricity of a substantially constant potential of about 1.5 volts.

12 is a resistance, preferably adjustable.

55 13 and 14 are suitable switches.

15 is a variable resistance such as the resistance box shown in Fig. 5 in which the resistance is varied through the rise and fall of the water in a tank 16; or as in Figs. 2 to 4, a temperature controlled rheostat as a 60 mercury thermometric rheostat in which the resistance varies with the temperature to which said device is exposed, as the device disclosed in my prior patent #800,792 of Oct. 3rd, 1905.

65 17, Fig. 5, is a relay controlling a local circuit containing, for example, two lamps 18 and 19 of different color adapted thereby to indicate at a distance from the recording device 10 and the tank 16 whether the 70 level of the liquid in said tank be above or below a predetermined height. Or, this local circuit may control other mechanical or electrical devices.

75 (a) and (b) are branches of a divided circuit in series with the source of potential 11 and resistance 12—the branch (a) containing in series the instrument 10, or instrument 10 and relay 17 as shown in Figs. 3 and 5; and the branch (b) the second or variable resistance 15. The junctions 20 and 21 of these branches are connected to the source of potential 11 by the leads 22 and 23. 24 and 25 are leads to the instrument 10; and 26 and 27 are leads to the variable resistance 15.

80 In Figs. 2, 4, and 5 I have shown the junctions 20 and 21 located in close proximity to the instrument 10.

85 In Fig. 3 I have shown the junction 20 located at one end of the divided circuit (the instrument end); and the junction 21 at the other, or resistance end. By this arrangement of the circuits, an approximate compensation for resistance temperature errors in the leads 25 and 26 is provided—the resistance introduced in each branch (a) and (b) through temperature changes along the leads being the same. Of course, the resistance changes of the lead 23 due to temperature variations would affect the accuracy of the reading, but this change in resistance is extremely small as compared to the total resistance of the circuit which is approximately 150 ohms for a potential at the battery 11 of from one to two volts.

90 100 105 In Fig. 4 I have shown several of the resistance branches (b), each containing a variable resistance 15 located at different points, and connected to a common indicating instrument 10 through suitable switches 110

28. By this arrangement I am enabled to indicate upon one and the same instrument, temperatures at various locations.

The operation of my system is as follows—
 5 reference being had to Fig. 1. The current from battery 11 passes through the resistance 12 to the junction 20 where it divides, part passing through the branch (a) and the remainder through the branch (b), uniting 10 at 21, and thence returning to the battery 11 through lead 23. The resistance 12 is made comparatively high, say 150 ohms for a potential of about 1.5 volts at the battery. An extremely small current thus flows, 15 thereby prolonging the life and maintaining the constancy of the battery 11. The resistance of the branch (a) is fixed; and is low, usually not more than several ohms including the resistance of the instrument 10. 20 The branch (b) contains the variable resistance 15 which is of several ohms, the resistance depending on the working range etc. The balance of the resistance of said branch depends upon the leads 26 and 27, 25 which resistance is a function of the length and cross-section of said leads, but which is kept as low as possible by providing sufficiently large conductors. The resistance of the branch (b) usually ranges from two to 30 five ohms, the greater part of which is to be included in the variable portion 15. This variable resistance is preferably of the mercury thermometric type as the device disclosed in prior patent #800,792 of Oct. 35 3rd, 1905, and comprises a mercury thermometer in the shank of which is a resistance wire or filament adapted to be short-circuited and vice versa by the mercury under the variations of temperature. By providing 40 this thermometric device with a scale suitably graduated, it may further serve to indicate the temperature directly at that point—the instrument 10 serving to indicate or record this temperature at a point re- 45 moved from said device. I prefer to make the resistance 12 adjustable in order to allow of the re-calibration or standardization of the instrument 10. This may readily be accomplished by holding the resistance 15 50 at a fixed and known temperature, and then adjusting the resistance 12 until the reading upon the instrument 10 corresponds. Or, I may cut out of circuit the entire branch (b) as by means of the switch 14, and adjust 55 the resistance 12 until the instrument 10 reads to a fixed, predetermined point. Any change in potential of the battery 11 may thus be detected and corrected for, it being necessary only to adjust the resistance 12 60 until the potential at the junction 20 is a predetermined amount—indicated by the reading on the instrument 10, as explained. The difference of potential between the junctions 20 and 21 must remain constant 65 unless changed by the variations of the

variable resistance 15, which variation is thus indicated or recorded by the instrument 10.

Although I have shown the system as specifically applied to the indicating or recording of temperature and temperature variations, it is very evident that it may likewise serve to indicate or record any physical change which will vary directly or can be made to vary the resistance of the branch 75 (b); or to measure resistances themselves, acting as a direct reading ohmmeter.

What I claim as new and desire to secure by United States Letters Patent, is:—

1. The combination with a source of electricity of a substantially constant potential, and a resistance and electrical apparatus in series therewith, of a shunt across said electrical apparatus including means whereby the resistance of the shunt is appreciably 85 varied by physical changes, the whole being so arranged that the said physical changes are automatically indicated by said electrical apparatus.

2. In an electrical system: a substantially 90 constant source of electro-motive force; a resistance and electrical apparatus in series therewith; and a shunt across said electrical apparatus including means whereby the resistance of the shunt is appreciably varied by 95 temperature, the whole being so arranged that the said temperature changes are automatically indicated by said electrical apparatus.

3. In an electrical indicating system: a 100 substantially constant source of electro-motive force; a resistance and electrical indicating means in series therewith; and a shunt across said indicating means, including means whereby the resistance of the shunt is 105 appreciably varied by physical changes, the whole being so arranged that the said physical changes are automatically indicated by said indicating means.

4. In an electrical indicating system: a 110 substantially constant source of electro-motive force; an adjustable resistance and electrical indicating means in series therewith; and a shunt across said indicating means including means whereby the resistance of the 115 shunt is appreciably varied by physical changes, the whole being so arranged that the said physical changes are automatically indicated by said indicating means.

5. In an electrical indicating system: a 120 substantially constant source of electro-motive force; an adjustable resistance and indicating means in series therewith; a shunt across said indicating means including means whereby the resistance of said shunt is 125 appreciably varied by physical changes, the whole being so arranged that the said physical changes are indicated by said indicating means; and means to cut in or out of circuit said shunt.

6. In an electrical indicating system; a substantially constant source of electro-motive force; a resistance and an indicating device in series therewith; a plurality of shunts across said indicating device, each shunt including means whereby the resistance of said shunt is appreciably varied by physical changes, the whole being so arranged that the said physical changes are automatically indicated by said indicating device; and means to individually cut in or out of circuit said shunts. 5
7. In an electrical indicating system for temperatures; a substantially constant source of electro-motive force; a resistance and electrical indicating means in series therewith; and a shunt across said electrical indicating means including means whereby the resistance of said shunt is appreciably varied by temperature, the whole being so arranged that the said temperature is automatically indicated by said indicating means. 15
8. In an electrical indicating system for temperatures; a substantially constant source of electro-motive force; a resistance and electrical indicating means in series therewith; a shunt across said indicating means; and a mercury thermometric resistance changing device located in said shunt. 20
9. In an electrical indicating and recording system: a substantially constant source of electro-motive force; a resistance and electrical indicating and recording means in series therewith; and a shunt across said indicating and recording means including means whereby the resistance of the shunt is appreciably varied by physical changes, the whole being so arranged that the said physical changes are automatically indicated and recorded by said indicating and recording means. 25
10. In an electrical indicating and recording system: a substantially constant source of electro-motive force; an adjustable resistance and electrical indicating and recording means in series therewith; and a shunt across said indicating and recording means whereby the resistance of the shunt is appreciably varied by physical changes, the whole being so arranged that the said physical changes are automatically indicated and recorded by said indicating and recording means. 30
11. In an electrical indicating and recording system: a substantially constant source of electro-motive force; an adjustable resistance and indicating and recording means in series therewith; a shunt across said indicating and recording means including means whereby the resistance of the shunt is appreciably varied by physical changes, the whole being so arranged that the said physical changes are automatically indicated and recorded by said indicating and recording means; and means to cut in or out of circuit 35 of said shunt. 60
12. In an electrical indicating and recording system: a substantially constant source of electro-motive force; a resistance and an indicating and recording device in series therewith; a plurality of shunts across said indicating and recording device each shunt including means whereby the resistance of the shunt is appreciably varied by physical changes, the whole being so arranged that the said physical changes are automatically indicated and recorded by said indicating and recording device; and means to individually cut in or out of circuit said shunts. 70
13. In an electrical indicating and recording system for temperatures: a substantially constant source of electro-motive force; a resistance and electrical indicating and recording means in series therewith; and a shunt across said electrical indicating and recording means whereby the resistance of the shunt is appreciably varied by temperature changes, the whole being so arranged that the said temperature is automatically indicated and recorded by said indicating and recording means. 75
14. In an electrical indicating and recording system for temperatures: a substantially constant source of electro-motive force; a resistance and electrical indicating and recording means in series therewith; a shunt across said indicating and recording means; and a mercury thermometric resistance changing device located in said shunt. 80
